MERCHANTISING MACHINE AND APPARATUS

Paul P. Scheurer, Wichita Falls, Tex., assignor to Will McKemie, Sr., Wichita Falls, Tex.

Application January 2, 1934, Serial No. 704,950

1 Claim. (Cl. 312—48)

This invention relates to merchandise machines and apparatus and it has particular reference to coin or token operated vending machines intended primarily for vending merchandise in the nature of foodstuffs of various kinds.

The principal object of the invention is to provide a vending machine designed for association with display windows of mercantile establishments and other places of business, serving to provide the purchasing public with a medium through which purchases may be made, either in emergencies or otherwise, particularly after closing hours.

Another object of the invention is to provide a mechanism operative by the aid of gravity, having first: an escapement mechanism, operated partially by the article of merchandise being vended, to insure against delivery of more than a single item at one operation, second, mechanism for locking the escapement mechanism against operation in the absence of a coin or token being deposited, third, mechanism to prevent the operation of more than one dispensing unit at a time where the units of the invention are in series, mechanism to insure the completion of a cycle of operation of each unit and mechanism to lock the actuating mechanism of the machine when the merchandise has been exhausted.

With the foregoing objects as paramount, the invention has particular reference to its salient features of construction and arrangement of parts which will become manifest as the description proceeds, taken in connection with the accompanying drawings, wherein:—

Figure 1 is an elevation in vertical section on lines 1—1 on Figure 2.

Figure 2 is a plan view of an assembly of dispensing units constructed according to the present invention.

Figure 3 is a perspective view of the escapement mechanism in control of the merchandise, one of which is employed in each of the units.

Figure 4 is a fragmentary view in perspective of an indicator and locking arm for disclosing whether or not the unit contains merchandise.

Figure 5 is a perspective view of the means for collectively locking the dispensing units against operation subject to the insertion of a coin into the machine and further shows the cycle ratchet.

Figure 6 is a fragmentary detail view of the locking switch which prevents operation of but a single unit at one time.

Figure 7 is a perspective view of a storage re-

ceptacle, one of which has operative connection with each of the units of the dispensing assembly, and

Figure 8 is a detail elevational view of a conventional type of coin operated chute employed in connection with the present invention.

Continuing with a more detailed description of the drawings, it may be first mentioned that the dispensing units of the invention are assembled in the relation shown in Figure 2 and that any number of such assemblies may be arranged side by side as desired to fill a predetermined space, such as that space usually provided for below the plate-glass of display windows in mercantile establishments. In Figures 1 and 2, 1 designates a front plate of such length as to embrace an assembly of dispensing units and constructed to define a receptacle 2, into which the merchandise from one or more of the dispensing units is discharged and in which the merchandise is accessible to the purchaser. An inclined floor 3 provides a passageway for the merchandise from its point of release to the receptacle 2 and during its travel along this passageway by gravity, it is required to raise a closure 4 which is pivoted at 5 and returned to closed position by gravity. This closure prevents unauthorized tampering with the concealed mechanism of the machine, since it is suspended for movement in one direction only.

The invention is designed to vend the character of merchandise which may be packed and sold in cylindrical receptacles or containers. This merchandise may include canned goods of all descriptions packed in cylindrical tins, as well as cereals and the like and where the merchandise is not furnished by the producer in cylindrical packages, a temporary covering of cylindrical design may be adopted so that the range of merchandise capable of being vended by the invention will not be limited.

Mounted for rotation on a shaft 6 in transverse relation to the chute or passage 3 is a merchandise retaining and releasing wheel 7, one of which is arranged at the inlet end of each of the passages 3. These wheels are in control of the articles of merchandise fed into the units from the storage receptacles shown in Figure 7, it being understood that the lower end of each of these receptacles is in communication with the inlet end of each of the passages 3 of the units. A description of this storage receptacle will be entered into presently.

Mounted on a shaft 8 and depending between the side walls 9 of the assemblies are a series of

links 10. These links support a shaft or rod 11 in parallel relationship with the shaft or rod 8. This arrangement is shown in detail in Figure 5. As will become apparent presently, the shaft 8 serves as a fulcrum for the depending links 10 and barrel shaft 11 when the machine is unlocked as by a coin, to enable the retaining and releasing wheel 7 to be actuated to release an article of merchandise from the storage receptacle. 10 Normally however, the rod 11 is rigid and cannot be moved by reason of a depending arm 12, integral with the intermediate link shown in Figure 5 and which arm has an angularly turned lower end 13, having a pin 14 at its extremity which 15 normally abuts a shoulder 15 of a pivoted arm 16 shown in dotted lines in Figure 1. More specific reference will be made to the mechanism last mentioned in the description of operation to follow presently, since this mechanism is associated with conventional coin actuated devices 20 as will be presently seen.

The escapement mechanism or the devices for controlling the retaining and releasing wheel 7 is comprised of an arcuately curved arm 17, shown in Figure 1 and in detail in Figure 3. To this arm is rigidly attached or made an integral part of the same, an anchor 18, having a projection 19, serving to limit the degree of rotation of the wheel 7. This anchor permits movement of the wheel 7 only to such extent as to release a single article of merchandise for movement to a point of accessibility in the receptacle 2, the next succeeding blade 20 of the wheel serving to intercept the passage of a succeeding article of merchandise to a point of discharge. The arcuate arm 17 and hence the anchor 18 pivots on a transverse shaft 21 and to the lower end of the arm 17 is connected the pull rod 22, the operative end of which rod extends through the front plate 1 and carries a knob 23. This rod 22 is the sole operating medium for the unit selected after the insertion of a coin.

Referring now particularly to the mechanism provided for preventing the operation of but a single unit at a time, it will be noted that a series of independently mounted plates 24 are arranged on a shaft 25 immediately below and in transverse relation to the operating rod 22. A detail view of this arrangement is shown in Figure 6. 45 These members 24 are constrained against other than horizontal sliding movement but, as stated, they are independently movable with respect to one another. Reference to Figures 1 and 6 will disclose that each of the operating rods 22 is 50 provided with a rigid pin 26, the latter being in such position thereon as to align with the point of contact between the members 24. When one of the rods 22 is pulled outwardly, the pin 26 carried thereby is moved between the contiguous members 24, it being pointed out that the members have deflected corners 27. Since the relative spacing of the members 24 is such as to admit only one of the pins 26 therebetween, only a single rod 22 can be pulled outwardly, the remaining members 24 resisting any effort to 55 actuate any of the companion rods. A shaft 28 serves as a stop to prevent undesired displacement of the members 24 by virtue of the fact that a depending portion 29 of each of the members 24 slidably engages this shaft.

As a means to notify a prospective purchaser of goods from the machine that the merchandise therein has been depleted, an arm 30 is mounted for pivotal movement on the shaft 8, as apparent 70 in Figures 1 and 4 and has a tail portion 31 ar-

ranged to normally rest upon the articles of merchandise entering the inlet end of the passage 3 of each of the units and thereby held in raised position. The opposite or forward end of the arm 30 carries a plate 32 bearing the words "full" 5 and "empty" or similar indicia, one of which words is visible at all times through an opening 33 in the front plate 1 of the assembly. When the machine contains merchandise, the tail portion 31 of the arm 30 is maintained in a raised 10 position to disclose the word "full" through the opening 33. When the last article of merchandise passes the tail portion 31 of the arm into the passage 3, the weight of the tail portion will cause the same to move downwardly, slightly 15 raising the plate 32, to thereby reveal the word "empty" in the opening 33. At the same time, a finger 34, integral with the bearing 35 on which the arm 30 operates, rotates a detent 36, one of which is provided for each of the units of the 20 assembly and all of which are mounted upon a transverse shaft 37. A detent 36 has an integral projection a, against which the finger 34 engages, a stop b, which rests upon the shelf 38 to limit its degree of movement and a third projection c 25 which lies in the path of the arcuate arm 17 only when the machine is emptied of merchandise. The detent will therefore prevent movement of the arcuate arm 17 and will therefore prevent the operating rod 22 from being pulled 30 outwardly.

However, when the store of merchandise is replenished in the machine, the tail portion 31 of the arm 30 will be raised, which operation will 35 actuate the depending finger 34 to rock the detent 36 to the dotted position shown in Figure 1. The interfering projection c of the detent will thereby be displaced to again allow the operating rod 22 to be pulled outwardly.

As a means to insure a complete cycle of movement of the elements when the operating rod 22 is actuated, a cycle ratchet is provided and shown only in Figure 5. This cycle ratchet is comprised of a detent 39, mounted for rotation on the shaft 37 and held normally in one position by a spring 41. A projection 42 carried by the detent is engageable with serrations or teeth 43 in an integral extension 44 of one of the depending links 10. It is apparent that as the lower end of the link 10 swings in an arcuate path, due to its pivotal suspension from the shaft 8, the projection 42 of the detent 39 will progressively engage the teeth 43 of the depending portion 44 until the full range of movement has been completed in one direction. This operation is repeated during movement in the opposite direction. Accordingly, at no time can the operating rod 22 be moved in and out without restraint when an effort is made to effect partial movement of the rod.

Referring now specifically to the storage receptacle shown in Figure 7 in detail, it will be noted that this receptacle is constructed of telescoped sections 45, the lowermost section 46 being angularly shaped so that the articles of merchandise contained therein may be properly directed into the passage 3 of each of the units of the invention. A recess 47 in the lower section 46 of the receptacle accommodates the tail portion 31 of the arm 30 previously described. It will be noted that a space 48 is provided in the 70 rear of the storage receptacle in order to render visible the merchandise therein so that an attendant may determine when the same is to be replenished.

The peculiar shape of the storage receptacle 75

as shown in Figure 7, renders the same effective when the invention is to be arranged in the space below the display windows of a store or the like. The upright sections 45 of the receptacle are disposed rearwardly of the display space of the window and therefore will interfere in no way with the view of the merchandise displayed by the merchant in the show window. The tubular portion of the lowermost section 46 is disposed beneath the floor of the show window, hence the merchandise may be delivered into the dispensing unit shown in Figures 1 and 2 at a point of convenience and accessibility immediately below the show window.

When a coin is deposited in the slot 49 in the front plate 1 and shown only in Figure 2, it passes through the conventional coin chute 50. Since this particular device is of conventional design and well known in the art, it is not considered necessary to enter into a detailed description of its construction and operation. It is considered sufficient to mention that the high degree of efficiency of this unit is such that spurious coins and slugs are ejected in such percentage as to render losses negligible. After passing through this unit, the coin 51, shown only in dotted lines in Figure 1 lodges between the pin 14 carried on the lower end of the arm 12 and a pin 52 carried by the arm 16. The arm 16 is pivoted at 53 and is spring actuated. The coin 51 therefore functions as an operating medium, since it will be remembered that without the presence of a coin, the pin 14 will engage the shoulder 15 of the arm 16 to prevent movement of the depending arm 12. Due to the presence of the coin however between the pins 14 and 52, the arm 16 is moved downwardly as the operating rod 22 of the machine is pulled outwardly, due to the wedging action of the coin between the stationary plate 54 and the pin 52 of the arm 16. Continuous movement of the rod 22 will cause the depending arm 12 to advance and discharge the coin 51 into a suitable receptacle below the machine, not shown.

The foregoing operation unlocks the arm 12 and as a result, the rod 11 is capable of free swinging movement and as the arcuate arm 17 is displaced by outward movement of the operating rod 22, the projection 19 carried by the

anchor 18 is raised to release the blade 20 of the wheel 7. This same operation however lowers the forward end of the anchor 18 in the path of the next blade 20 of the wheel 7 to prevent rotation of the wheel 7 beyond a predetermined point. When the operating arm 22 is returned to normal position, the projection 19 of the anchor 18 assumes its position in the path of the next succeeding blade 20 of the wheel 7. The merchandise is thus released to pass into the receptacle 2 at the front of the machine while the next succeeding article of merchandise is intercepted by the wheel 7.

Manifestly, the construction shown is capable of considerable modification and such modification as is considered within the scope and meaning of the appended claim is also considered within the spirit and intent of the invention.

What is claimed is:

In a merchandising machine, the combination comprising a housing having inclined passages normally closed against entry through their discharge ends and merchandise magazines from which articles of merchandise are gravitationally fed into said passages, a shaft mounted above the inlet ends of said passages, a series of peripherally recessed wheels rotatably mounted on said shaft and extending into the path of movement of said articles to singly admit them into said passages, a discharge receptacle common to each of said passages, an escapement means provided to control each of said wheels, each of said escapement means comprising an actuating plunger and an arcuately shaped arm pivotally connected to said plunger at one end and at its other end to a shaft disposed above and parallel to said first shaft, an anchor member rigidly affixed to said arcuate arm having on its forward edge a downwardly extending projection and on its rear edge a depending lip, whereby said projection will engage a recess of said wheel in the inner position of said plunger to prevent rotation thereof and be released from said recess with the simultaneous positioning of said lip into the path of said recess in the outward position of said plunger.

PAUL P. SCHEURER.
